UNITED STATES PATENT OFFICE.

THOMAS J. SHEARMAN, OF PHILADELPHIA, PENNSYLVANIA.

THREAD-CUTTING DEVICE.

Application filed April 12, 1921. Serial No. 460,610.

To all whom it may concern:

Be it known that I, THOMAS J. SHEARMAN, a citizen of the United States, residing at Philadelphia, in the county of Philadelphia and State of Pennsylvania, have invented certain new and useful Improvements in Thread-Cutting Devices, of which the following is a specification.

A number of thread-cutting devices have 10 been invented, prior to my present invention, which are capable of threading the ends of pipes in such manner that the threaded portions taper in the direction of the length of the pipes. These prior art devices, however, are not completely satisfactory since they have a number of objectionable features. For example it sometimes occurs that small particles of metal lodge to the rear of one of the dies in a manner not 20 noticeable to the workman and after the threading takes place there is an inaccurate cut which is likely to cause a leaky joint when the screw threaded end is fitted into a screw threaded opening. A still further 25 disadvantage of said prior art structures is that dirt and chips often clog and prevent free movement of the dies in their guideways and the removal of this dirt is comparatively difficult and takes considerable 30 of the time of the workman.

One object of my invention is to provide a threading device of the above general type in which the dies will accurately move in a predetermined path so that the cut will be 35 under positive control at all times and furthermore that the dies will not accidentally move out of their guideways.

Another object is to so construct the device of my invention that the dies can be 40 quickly and easily removed and replaced; said dies being so made that by changing their position they will thread pipes of different diameters.

A further object is to so arrange the parts 45 that the guideways for the dies will not clog up with dirt but on the contrary the structure will permit a free sliding movement of the dies at all times during the operation of the device.

50 A still further object is to make the device in such manner that it will be well balanced and can be easily manipulated to accurately position it on a pipe to start a cut.

55 These objects, and other advantageous ends which will be described hereinafter, I

attain in the following manner, reference being had to the accompanying drawings in which—

Figure 1 is a top plan view of a pipe 60 threading device made in accordance with my invention,

Figure 2 is a sectional elevation taken on the line 2—2 of Figure 1,

Figure 3 is a fragmentary section taken 65 on the line 3—3 of Figure 2,

Figure 4 is a fragmentary section taken on the line 4—4 of Figure 1,

Figure 5 is a detail face view of one of 70 the die retaining members,

Figure 6 is a section taken on the line 6—6 of Figure 5,

Figure 7 is a fragmentary elevation of a die guiding post made in accordance with my invention and showing the same secured in 75 its retaining ring; the retaining ring being illustrated in section,

Figure 8 is an elevation of one side of Figure 7, and

Figure 9 is an elevation of the opposite 80 side of Figure 7.

Referring to the drawings, 10 represents a metallic head which includes a central integral depending nipple 11 which is externally screw threaded as shown at 12. The 85 external screw threads of the nipple 11 are adapted to screw into the internal screw threads 13 of a sleeve 14. This sleeve 14 adjacent its bottom has an internal annular flange 15, the inner surface of which is 90 machine finished to a predetermined diameter to permit a clamping and centering collar 16 to be fitted therein so that it can be readily removed. Clamping collars 16 having various internal diameters can be attached to the flange 15 to suit pipes of various external diameters by means of clamping screws 12^a which extend through the sleeve; said clamping collars 16 having holes into which the inner ends of the clamping 100 screws extend as clearly shown in Figure 2. These clamping screws 12^a, when the pipe to be fitted is inserted through the clamping collar, can be turned so as to jam against the outer surface of the pipe while extending 105 upwardly through the collar 16, sleeve 14 and nipple 11.

The top portion 17 of the head 10 at points on opposite sides of the axis of the nipple 11 has upwardly extending flanges 110 18 which are spaced apart; the inner surfaces 19 of said flanges on each side being

22

straight and parallel so as to provide guideways 20 for the dies 21; said dies having opposite side surfaces parallel and accurately fitting between the surfaces 19 so as to 5 freely slide in the guideways. The guideways 20 extend without obstruction to the end surfaces of the head and the top portion 17 of the head on either side of the axis of the nipple 11 has holes 23; said 10 holes communicating with the bottoms of the guideways between the flanges 18. The bottoms of the guideways adjacent the surfaces 19 are preferably shaped to provide sliding ledges 24 upon which the dies 21 15 may slide between surfaces 19 which hold them against lateral movement. The top part of the head adjacent the ledges, is channelled, as shown at 25, thereby providing rigidly supported ledges with narrow bearing surfaces.

20 A ring 26 rotatably fits the outer surface of the sleeve 14 below the external flange 27 of said sleeve; said external flange forming a shoulder for preventing the ring 26 25 from moving upward relatively to the sleeve 14. At a position below the ring 26 the sleeve 14 has external screw threads 28 upon which is screwed a ring nut 29; said ring nut serving to prevent downward movement 30 of the ring 26 relative to the sleeve 14.

Two posts 30, which may be made from cylindrical metallic rods, have their lower ends screw threaded and fitting within tapped holes in the ring 26. These posts 35 have their axes slanting upwardly with respect to the axis of the nipple 11 and project through channel 25, the holes 23, the guideways 20, and holes 31 in the dies 21. The holes 31 have a contour which registers 40 with the curved cross sectional contour of the posts 30 and are located entirely between the opposite ends 32 and 33 of the dies 21. Thus when there is no relative 45 rotatable movement between the head 10 and the sleeve 14, the dies 21 cannot move in their guideways either toward or from the axis of the nipple 11.

50 The flanges 18 of the head 10 have lateral projections 34, the upper surfaces of which are preferably flush with the top edges of the surfaces 19. Cover members 35 bridge the tops of the guideways 20 and extend across the tops of the dies 21. These cover members 35 are secured to the head 10 by means of screws 36; said screws 55 fitting within tapped holes in the portions 34 of the head 10. The screw 36 at one end of the cover member 35 on each side extends through a hole 37 in said cover member while the screw 36 at the opposite end extends through a notch 38 in the cover member on each side of the device as clearly shown in Figure 1; the detail construction 60 of the similarly constructed cover members 35 being clearly shown in Figures 5 and 6.

Each of the posts 30 is cut away at its opposite sides to provide parallel surfaces 39 and 40; said surfaces being flat and also being parallel with the axis of the nipple 11. The surface 40 of each post terminates 70 at its upper end in a shoulder 41; said shoulder being in such position as to be substantially on the same level with the upper surface of the cover member 35 on each side of the device. Thus when the 75 parts are in their operative assembled position, as shown in Figures 1 and 2, the upper end portions of the posts project through slots 42 in the cover members 35; said slots at their portions where the upper 80 parts of the posts project therethrough being of a width substantially equal to the thickness of the posts between the surface 40 and the opposite sides of the post so that the shoulders 41 project over the top surfaces 85 of the members 35 as clearly shown in Figure 2. The opposed surfaces 39 terminate in shoulders 43 and serve to limit the downward movement of the head by engagement with the bottom portions of the dies when the head is rotated relatively to the sleeve 14 during the threading operation. Each of the slots 42 adjacent one end has an enlarged portion 44 corresponding to the cross section of the posts above the shoulders 41 so that when it is desired to remove or change the positions of the dies 21 it is merely necessary to remove the screws 36 from the holes 37 and loosen the other screws 36 after which the cover members 35 can be slid to bring the enlarged portions 44 of the slots 42 in register with the posts 30 and at the same time the notches 38 will be free of said latter mentioned screws and the members 35 can be raised 100 bodily, after which the dies can be lifted 105 out of their guideways.

The ends 32 of the dies 21 have threading portions 45 which are adapted to thread 110 pipes of one diameter while the opposite ends 33 of the dies have threading portions 46 adapted, when the dies are reversed, to thread pipes of another diameter.

115 The head 10 at opposite sides of the posts 30 have depending arms 47 which have sockets 48 into which handle levers can be inserted so as to permit the rotation of the head 10 to effect the threading of the end of a pipe which is secured by the clamping screws 12 and which extends through the 120 collar 16, sleeve 14 and nipple 11 and between the adjacent ends of the dies 21. During the threading action the rotation of the head due to the screw threaded connection between the nipple 11 and sleeve 14 125 will cause the head to be lowered with respect to the pipe and the dies will cut initially at their greatest depths and during the downward movement of the head the dies under the control of the posts 30 will 130

move away from the axis of the pipe and nipple 11 and in this manner the threaded portion of the pipe will taper in the direction of the length of the pipe. During this 5 action the dies must move outwardly in a path prescribed by the slanting disposition of the posts 30 and since the holes 31 in the dies slidably fit the curved cross section of the posts as shown in Figure 3, it is impossible 10 for the dies to move inwardly during the downward movement of the head. The parallel straight surfaces 39 and 40 permit the cover members 35 to move downward in a straight path parallel with the axis of the 15 nipple 11 so that these cover members do not change their position relatively to said axis during the downward movement of the head.

By having the arms 47 depend as illustrated 20 the line of handle connection is placed in a well balanced position so that the device can be readily handled and applied to a pipe and at the same time there is no obstruction of any character at the 25 outer ends of the guideways. Therefore if there is any dirt which lodges on the ledges 24, during the outward movement of the dies, this dirt will merely be pushed over the ends of the guideways when it reaches 30 the end surfaces 22. Furthermore any dirt which clogs in the space 25 can either pass over the end 22 or drop through the nipple 11 or through the holes 23.

While I have described my invention as 35 taking a particular form, it will be understood that the various parts of my invention may be changed without departing from the spirit thereof, and hence I do not limit myself to the precise construction set 40 forth, but consider that I am at liberty to make such changes and alterations as fairly come within the scope of the appended claims.

Having thus described my invention, what 45 I claim as new and desire to secure by Letters Patent is:—

1. A thread-cutting device including a rotatable head having flanges spaced apart and providing guideways; dies slidable in the 50 guideways; guide posts slanting relatively

to the axis of the head and taking through the dies; members bridging the guideways and having slots adapted to embrace the guide posts, the parts of the guide posts which take through the slots having faces 55 parallel to the axis of the head whereby the bridge members may move upwardly or downwardly without changing their distance from the axis of the head.

2. A thread-cutting device including a 60 rotatable head having flanges spaced apart and providing guideways having ledges therein; dies having holes and slidable in said guideways on said ledges between the flanges, said head being cut away to provide 65 spaces in said guideways below the ledges and having upright holes communicating with said spaces; guiding posts slanting relatively to the axis of said head and extending through said holes in the head and dies; 70 and means for moving said head relatively to said posts in the direction of its axis and relatively to the length of said guiding means; substantially as described.

3. A thread-cutting device including a 75 rotatable die-carrying head having flanges spaced apart and providing guideways; dies 80 slidable within said guideways and having holes therein; guiding posts slanting relatively to the axis of said head and extending through said die holes above said guideways; and slotted members detachably secured to said head and bridging said guideways, said posts having cut-out portions providing surfaces parallel with the axis of 85 said head and terminating in shoulders, said posts having said cut-out portions slidably fitting said slots so that the shoulders abut the upper surfaces of said members, said slots having enlarged portions movable into 90 register with said posts to permit said members and dies to be lifted over said posts; substantially as described.

In testimony whereof I have signed my name to this specification in the presence of 95 two subscribing witnesses.

THOMAS J. SHEARMAN.
